Primary Examiner—Cathron C. Brooks*Assistant Examiner*—Maurice Stevens(74) *Attorney, Agent, or Firm*—Ostrager Chong Flaherty & Broitman P.C.(57) **CLAIM**

The ornamental design for an interior archway for an aircraft, as shown and described.

DESCRIPTION

FIG. 1 is a perspective view of the interior archway for an aircraft;

FIG. 2 is a front plan view of the interior archway for an aircraft, with the back plan view being a mirror image thereof;
FIG. 3 is a cross-sectional view of the interior archway for an aircraft as shown in FIG. 2;FIG. 4 is a top plan view of the interior archway for an aircraft;
FIG. 5 is a bottom plan view of the interior archway for an aircraft; and,FIG. 6 is a first end view of the interior archway for an aircraft.
The broken lines shown in FIG. 1 illustrate unclaimed portions of an interior archway for an aircraft and form no part of the claimed design.**1 Claim, 2 Drawing Sheets****US D606,923 S**
